Kelly

[11] Patent Number: Des. 328,401

[45] Date of Patent: ** Aug. 4, 1992

[54] COMBINED END CONNECTOR AND PEDESTAL FOR NESTABLE COT OR THE LIKE

895,898 8/1908 Scheer D6/382
4,958,390 9/1990 Mendenhall 5/111

[75] Inventor: Ray G. Kelly, St. Louis, Mo.

Primary Examiner—Melvin B. Feifer
Attorney, Agent, or Firm—Paul M. Denk

[73] Assignee: Angeles Nursery Toys, Inc., Pacific, Mo.

[57] **CLAIM**
The ornamental design for a combined end connector and pedestal for nestable cot or the like, as shown and described.

[**] Term: 14 Years

DESCRIPTION

[21] Appl. No.: 479,727

FIG. 1 is a front view of a combined end connector and pedestal for nestable cot or the like showing my new design;

[22] Filed: Feb. 14, 1990

FIG. 2 is a right side view thereof, the left side being a mirror image;

Related U.S. Application Data

FIG. 3 is a bottom view thereof;

[63] Continuation-in-part of Ser. No. 461,326, Jan. 5, 1990,
Pat. No. 5,003,649.

FIG. 4 is a rear view thereof;

[52] U.S. Cl. D6/495; D8/382

FIG. 5 is a top view thereof;

[58] Field of Search D6/382, 392, 491, 503,
D6/495; D8/382; 5/8, 11, 288

FIG. 6 is a front view of a second embodiment of the
design of FIG. 1, the only difference being the extension
of the pedestal;
